17 Claims. (Cl. 250—36)

The invention relates to a device intended to generate a voltage which increases linearly with the time and comprising a condenser, a source of direct voltage and a resistance through which the condenser is charged.

Such a circuit-arrangement is chiefly utilized in television transmitting and receiving systems which comprise a cathode ray tube and in which a device generating a saw-tooth current or voltage is utilized for the control of the scanning movement of the beam of cathode rays. In such systems it is desirable that the controlling voltage should increase linearly with the time. The known controlling devices for generating a saw-tooth current or voltage comprise a condenser, a source of direct voltage and a resistance through which the condenser is charged by the source of direct voltage while a discharge tube connected in parallel with the condenser serves to discharge the condenser periodically.

Turning now to the drawing, in which Fig. 1 illustrates diagrammatically a simplified circuit diagram for aiding in the explanation of our invention;

Fig. 2 shows diagrammatically a circuit embodying our invention; and

Figs. 3 and 4 show schematically modifications of the embodiment of our invention shown in Fig. 2.

Our invention will be explained in detail.

Such a known device for generating a saw-tooth current or voltage is represented in Figure 1 of the accompanying drawing in which 1 denotes a source of voltage, 2 a condenser, 3 a discharge tube and 4 a resistance through which the condenser 2 is charged.

The operation of such a circuit arrangement is as follows:

The condenser 2 is charged by the source of voltage 1 through a resistance 4 with a rapidity which is determined by the values of the resistance 4 and of the condenser 2, until the ignition voltage of the discharge tube 3 which may contain a control electrode is attained or until, as is customary in television systems, a voltage impulse is produced on the grid of the tube 3. At this moment the condenser suddenly discharges and the charging process recommences.

The instantaneous value of the voltage set up across the condenser 2 increases during the charging period linearly with the time if the charging current of the condenser 2 is constant. To that end it has previously been proposed to charge the condenser 2 through a variable im-

pedance formed by a saturated diode or by a screen grid tube.

Where such type variable impedances are used, it is inexpedient to ground one pole of all the batteries, since short circuits would result. The use of these additional potential sources arises from the fact that in addition to the potential source for charging the condenser, a source of voltage must be supplied for heating the filament and in the case of a screen grid tube, biasing batteries must also be provided. Accordingly, the voltage sources "float" above ground potential. Furthermore, the capacities of said batteries relatively to earth, form part of the circuit which determines the frequency of the oscillations generated, with the result that the frequency which can be obtained with the circuit-arrangement is decreased.

The object of the invention is to provide a device for generating a voltage which increases linearly with the time and to obviate the above mentioned disadvantages.

This is obtained in the circuit-arrangement according to the invention owing to the fact that in the charging circuit operates an emf. derived from the condenser voltage and being equal and oppositely directed to the condenser voltage.

In one particular mode of realization of the circuit-arrangement according to the invention the emf. derived from the condenser is taken from the anode circuit of the last tube of an even number of cascade-connected discharge tubes to which the voltage set up across the condenser is applied.

The emf. derived from the condenser may likewise be taken from the anode circuit of the last of an odd number of cascade-connected discharge tubes if an odd number of these tubes are formed by a multi-grid tube whose electrode voltages are adjusted in such manner that in the anode circuit of the multi-grid tube is set up a voltage which is in phase with the voltage supplied to the grid.

Figure 2 represents a circuit-arrangement for generating a saw-tooth voltage required for scanning purposes in television systems, comprising a condenser 2, a source 1 of direct voltage and a resistance 4 through which the condenser 2 is charged by the source 1 of direct voltage. The condenser discharges periodically through a discharge tube 3, periodical impulses being supplied to the grid of said tube to control the initiation of the discharge. The voltage set up across the condenser 2 is supplied through a condenser 5 to a discharge tube 6 between the

- grid and the cathode of which is located a leakage resistance 7. The voltage set up in the anode circuit of the tube 6 across a resistance 8 is preferably supplied to the deflecting plates of a cathode ray tube. In order to ensure that the voltage set up across the condenser 2 increases linearly with the time, the voltage produced in the anode circuit of the tube 6 is applied via grid condenser 8 and a leakage resistance 10 to the grid of a tube 11 in the anode circuit of which is located a resistance 12 a point 13 of which is connected to that end of the resistance 4 which is remote from the condenser 2. With the above-described circuit-arrangement that portion of the resistance 12 which is located between the point 13 and the positive terminal of the source of voltage 1 is included in the charging circuit which comprises the source of voltage 1 (which acts at the same time as the source of anode voltage for the tubes 6 and 11) the resistance 4 and the condenser 2. According to the invention, the point 13 is so chosen that the voltage set up across said portion of the resistance 12 is equal to the voltage produced across the condenser 2. The direction of the voltage set up across said portion of the resistance 12 in the charging circuit is opposite to the condenser voltage. With the circuit-arrangement described it is ensured that during the charging period the voltage set up across the condenser increases linearly with the time. The explanation thereof is as follows:
- In the charging circuit applies the equation $+E = e_1 + e_4 + e_{12}$, in which E denotes the voltage of the source 1 of direct voltage, e_2 the voltage set up across the condenser 2, e_4 the voltage across the resistance 4 and e_{12} the voltage across that portion of the resistance 12 which is included in the charging circuit. If in this equation during the charging period $e_2 = -e_{12}$, or in other words if in the charging circuit a voltage is operative which is equal and oppositely directed to the condenser voltage, which may be obtained by an adequate choice of the number of stages of amplification connected after the condenser 2 and by the correct adjustment of the point 13, the voltage e_4 across the resistance 4 is constant during this period. In this case the condenser is charged with a constant current with the result that the voltage across the condenser 2 increases linearly with the time.

In the circuit-arrangement described it is possible, however, that due to the presence of the condenser 5 and of the resistance 7 the increase of the voltage with the time is not completely linear. This is caused by the fact that with a view to the tube 6 the resistance 7 may not be taken of any desired high value. In this case the current flowing through the resistance 7 is no longer negligible with respect to the charging current. According to the invention, this drawback can be removed by adjusting the point 13 of the resistance 12 in such manner that the emf. acting in the charging circuit is equal to the condenser voltage multiplied by

$$1 + \frac{R_1}{R_2}$$

wherein R_1 and R_2 denote the values of the resistances 4 and 7 respectively. That with this adjustment of the point 13 the condenser voltage increases linearly with the time ensues from the following equations:

$$E = (R_1 + e_2 + e_{12}) \quad (1)$$

$$e_2 = i_1 R_2 \quad (2)$$

$$i_1 = i_2 + i_3 \quad (3)$$

wherein E denotes the voltage of the source 1 of direct voltage, i_1 the charging current of the condenser 2, i_2 the current flowing through the grid leakage resistance 7, i_3 the current flowing through the resistance 4, e_2 the voltage across the condenser 2, e_{12} the voltage across that portion of the resistance 12 which is included in the charging circuit, e_1 the value of the voltage across the resistance 4 and e_2 the value of the voltage across the grid leakage resistance 7.

From the Equations (1), (2) and (3) may be deduced:

$$E = (i_1 + i_2) R_1 + e_2 + e_{12}$$

or

$$E = i_1 R_1 + e_2 \left(\frac{R_1}{R_2} + 1 \right) + e_{12} \quad (15)$$

If in this equation during the charging period

$$e_2 \left(\frac{R_1}{R_2} + 1 \right) = -e_{12} \quad (20)$$

the charging current of the condenser 2 is constant during this period with the result that the voltage of the condenser increases linearly with the time.

Another measure which may be utilized in accordance with the invention in order to compensate the deflection produced by the resistance 7 consists in connecting a point located between the ends of the grid leakage resistance 7 to a point which has relative to the cathode a voltage which is equal to and in phase with the voltage set up between the grid and the cathode of the tube 6. In this case the current flowing through the resistance 7 remains zero at every moment and can consequently no longer act on the charging current of the condenser 2. Besides, owing to this measure the condenser 5 may be taken much smaller without any influence being exerted on the shape of the curve representing the instantaneous value of the voltage as a function of the time. The voltage to be supplied to the point located between the ends of the leakage resistance 7 may be taken from the anode circuit of one of the discharge tubes in the circuit arrangement.

One mode of realization of a device for generating a saw-tooth voltage in which the above-mentioned measure has been carried out is represented in Figure 3 in which between a point 14 of the resistance 7 and the cathode of the tube 6 is applied a voltage which is equal to and in phase with the voltage set up between the grid and the cathode of the tube 6, owing to the fact that the point 14 is connected through a blocking condenser 15 to that end of the resistance 4 which is connected to the anode circuit of the tube 11. For the rest the circuit-arrangement is completely similar to the circuit-arrangement of Figure 2. An advantage of the last-mentioned measure of compensating for the influence of the grid leakage resistance 7 relatively to the first-mentioned measure is that it is independent of the value of the resistance 4 whereas the first-mentioned measure is dependent on the value of the resistance 4 and therefore on the amplitude of the oscillations to be generated.

Figure 4 represents a circuit-arrangement which is preferably utilized for controlling the scanning movement of a beam of cathode rays in a cathode ray tube with electrostatic control for television transmitting or receiving purposes.

With this circuit-arrangement a saw-tooth voltage is set up by means of a source of voltage 1, a condenser 2, a resistance 4 and a discharge tube 3 to which are supplied the synchronizing

5 impulses which cause the condenser 2 to discharge. The saw-tooth voltage set up across the condenser 2 is supplied in known manner to the tubes 6 and 11 connected in cascade. The grid of the tube 11 is connected to such a point of the 10 output circuit of the tube 6 that the saw-tooth voltage set up between the grid and the cathode of the tube 11 is equal to and in phase with the voltage of the grid of the tube 6 relative to the 15 cathode with the result that in the output circuits of the tubes 6 and 11 across the resistances 8 and 12 voltages are set up which are equal to and in counterphase with each other. Each of the ends of the resistances 8 and 12 which are connected to the 20 anode of the corresponding tube is connected, to one of the deflecting plates 16 and 17 of a cathode ray tube, said plates being destined to control the beam of cathode rays. If it is desired, the deflecting plates, instead of being connected directly across the resistors 8 and 12 may 25 be connected by condensers inserted in series with the connection between the plates and the resistors and a leakage resistor connected directly across the plates 16 and 17. In the circuit-arrangement described the voltage in the median plane between the deflecting plates is constant as is desired with cathode ray tubes in order to prevent distortion of the picture received.

30 In order to ensure in the circuit-arrangement described that the voltage between the plates 16 and 17 increases linearly with the time, an emf. which is equal to and has the opposite direction of the condenser voltage is taken from the anode circuit of the tube 11 owing to the fact that a 35 point 13 of the resistance 12 is connected to that end of the resistance 4 which is remote from the condenser 2. If desired, the influence of the resistance 7 in this circuit-arrangement may be suppressed by adjusting the point 13 in such 40 manner that the voltage between this point and the end of the resistance 12 which is connected to the positive terminal of the source of direct voltage is equal to the voltage set up across the condenser 2 multiplied by the factor

$$45 \left(\frac{R_1}{R_2} + 1 \right).$$

50 Preferably, however, a voltage which is equal to and in phase with the voltage set up between the grid and the cathode of the tube 6 is applied between a point of the grid leakage resistance 7, and the cathode of the tube 6 by connecting the 55 end of the resistance 4 which is remote from the condenser 2 through a condenser 15 to a point of the grid leakage resistance 7.

Having described our invention, what we claim is:

1. A sweep oscillator comprising a source of 60 voltage, a condenser, a resistance, an impedance, means to connect all of said elements in series, and feedback means to vary the potential drop across only the impedance as a function of the stored energy of the condenser.

2. A sweep oscillator comprising a source of 65 voltage, a condenser, a resistance, an impedance, means to connect all of said elements in series, and means to decrease the potential drop of only the impedance in proportion to the potential rise of the condenser.

70 3. A sweep oscillator comprising a source of voltage, a condenser, a resistance, an impedance, means to connect all of said elements in series, and feedback means to maintain the potential drop across the resistance independent of the condenser voltage.

4. A sweep oscillator comprising a source of voltage, a condenser, a resistance, an impedance, means to connect all of said elements in series, whereby energy is stored in the condenser with a consequential rise in potential thereacross, and means to vary the voltage across the impedance in an equal and opposite fashion to the variation of voltage across the condenser. 5

5. A sweep oscillator comprising a source of voltage, a condenser, a resistance, an impedance, 10 means to connect all of said elements in series, whereby energy is stored in the condenser, means to supply input energy to thermionic amplifier in accordance with the energy stored in the condenser, and means to impress upon the impedance 15 energy from the thermionic amplifier.

6. A sweep oscillator comprising a source of voltage, a condenser, a resistance, an impedance, means to connect all of said elements in series, whereby energy is stored in the condenser, a 20 thermionic amplifier having an input and output circuit, means to supply energy to the input circuit of the amplifier in accordance with the energy stored in the condenser, and means to connect the output circuit of the amplifier to the 25 impedance.

7. A sweep oscillator comprising a source of voltage, a condenser, a resistance, an impedance, means to connect all of said elements in series, whereby energy is stored in the condenser with 30 a consequential rise in potential thereacross, an even number of amplifying stages connected in cascade, an input circuit and an output circuit for the cascade connected stages, means to supply energy to the input circuit in accordance with 35 the voltage developed across the condenser, and means to connect the output circuit across the impedance.

8. A sweep oscillator comprising a source of voltage, a condenser, a resistance, an impedance, 40 means to connect all of said elements in series, whereby energy is stored in the condenser with a consequential rise in potential thereacross, an even number of amplifying stages connected in cascade, an input circuit and an output circuit 45 for the cascade connected stages, means to supply energy to the input circuit in accordance with the voltage developed across the condenser, means to connect the output circuit across the impedance, and means to adjust the voltage developed 50 across the impedance to equal the voltage developed across the condenser.

9. A sweep oscillator comprising a source of voltage, a condenser, a resistance, an impedance, means to connect all of said elements in series, 55 whereby energy is stored in the condenser with a consequential rise in potential thereacross, an even number of amplifying stages connected in cascade, a serially connected condenser and resistance input circuit for the cascade connected 60 stages, an output circuit for the cascade connected stages, means to supply energy to the input circuit in accordance with the voltage developed across the condenser, and means to connect the output circuit across the impedance, and 65 means to adjust the voltage developed across the impedance to equal the voltage developed across the condenser multiplied by one plus the ratio of the resistance connected in series with the condenser to the resistance in the input circuit. 70

10. A sweep oscillator comprising a source of voltage, a condenser, a resistance, an impedance, means to connect all of said elements in series, whereby energy is stored in the condenser with a 75

- consequential rise in potential thereacross, an even number of amplifying stages connected in cascade, a serially connected condenser and resistance input circuit for the cascade connected stages, an output circuit for the cascade connected stages, a condenser connected between the junction point of the impedance and the resistance connected in series with the impedance and to an intermediate point of the resistance in the input circuit, means to supply energy to the input circuit in accordance with the voltage developed across the condenser, and means to connect the output circuit across the impedance, and means to adjust the voltage developed across the impedance to equal the voltage developed across the condenser multiplied by one plus the ratio of the resistance connected in series with the condenser to the resistance in the input circuit.
11. A sweep oscillator comprising a source of voltage, a condenser, a resistance, an impedance, means to connect all of said elements in series, means to vary the potential drop across only the impedance as a function of the stored energy of the condenser, and a discharge tube connected across the condenser.
12. A sweep oscillator comprising a source of voltage, a condenser, a resistance, an impedance, means to connect all of said elements in series, whereby energy is stored in the condenser, means to drive a thermionic amplifier in accordance with the energy stored in the condenser, means to impress upon the impedance energy from the thermionic amplifier, and a discharge tube connected across the condenser.
13. A sweep oscillator comprising a two stage resistance-capacity coupled thermionic amplifier, having an input and an output circuit, a condenser connected across the input circuit, a resistance connected from the output circuit to the condenser, a thermionic discharge tube connected across the condenser, and a power supply in series with at least a portion of the output circuit, said resistance and said condenser.
14. In a sweep oscillator wherein is provided a condenser for storing energy, the method of generating a voltage which increases linearly with respect to time, which comprises the steps of producing a source of voltage, charging the con-

denser from the source of voltage thereby producing a potential drop across the condenser, amplifying the produced potential drop, deriving a portion of the amplified potential drop, and injecting the derived potential drop in series with the condenser and the source of voltage.

15. In a sweep oscillator wherein is provided a condenser for storing energy, the method of generating a voltage which increases linearly with respect to time, which comprises the steps of producing a source of voltage, charging the condenser from the source of voltage thereby producing a potential drop across the condenser, amplifying the produced potential drop, deriving a portion of the amplified potential drop equal to the potential drop across the condenser, and injecting the derived potential drop in series with the condenser and the source of voltage.

16. In a sweep oscillator wherein is provided a condenser for storing energy, the method of generating a voltage which increases linearly with respect to time, which comprises the steps of producing a source of voltage, charging the condenser from the source of voltage thereby producing a potential drop across the condenser, amplifying the produced potential drop, deriving a portion of the amplified potential drop equal to the potential drop across the condenser, and injecting the derived potential drop in series with the condenser and the source of voltage.

17. In a sweep oscillator wherein is provided a condenser for storing energy, the method of generating saw-tooth voltage waves which comprises the steps of producing a source of voltage, charging the condenser from the source of voltage thereby producing a potential drop across the condenser, amplifying the produced potential drop, deriving a portion of the amplified potential drop equal to the potential drop across the condenser, injecting the derived potential drop in series with the condenser and source of voltage and in opposite polarity to the potential drop across the condenser.
